CARBON DIOXIDE FIRE EXTINGUISHER DISCHARGE HORN

Charles K. Huthsing, Jr., 1685 Shermer Road,
Northbrook, Ill.

Filed Oct. 25, 1960, Ser. No. 62,616

Term of patent 14 years

(Cl. D16—2)

Figure 1 is a top plan view of a carbon dioxide fire extinguisher discharge horn showing my new design;

Figure 2 is a side elevational view thereof;

Figure 3 is a rear end elevational view thereof taken from the left of Figure 2; and

Figure 4 is a front end elevational view thereof taken from the right of Figure 2.

I claim:

The ornamental design for a carbon dioxide fire extinguisher discharge horn, as shown.
